United States Patent

Des. 242,025
Patented Oct. 26, 1976

242,025

CLOCK OR SIMILAR ARTICLE

James O. O'Brien, 2101 Hawk Lane,
Rolling Meadows, Ill. 60008

Filed Mar. 28, 1975, Ser. No. 562,972

Term of patent 14 years

Int. Cl. D10—01

U.S. Cl. D10—8

FIG. 1

FIG. 2

FIG. 1 is a front elevational view of a clock or similar article showing my new design; and

FIG. 2 is a top plan view thereof, the bottom being plain and unornamented.

I claim:

The ornamental design for a clock or similar article, substantially as shown and described.
